UNITED STATES PATENT OFFICE.

ALBERT W. BALLENGER, OF YORK, NEBRASKA.

DESIGN FOR A BADGE, EMBLEM, OR SIMILAR ARTICLE OF MANUFACTURE.

52,624.

Specification for Design.

Patented Nov. 12, 1918.

Application filed August 31, 1918. Serial No. 252,263. Term of patent 3½ years.

To all whom it may concern:

Be it known that I, ALBERT W. BALLENGER, a citizen of the United States, residing at York, in the county of York and State of Nebraska, have invented a new, original, and ornamental Design for a Badge, Emblem, or Similar Article of Manufacture, of which the following is a specification, reference being had to the accompanying drawing, forming part thereof.

The figure is a face view of a badge, em-

blem, or similar article of manufacture showing my new design.

I claim:

The ornamental design for a badge, emblem, or similar article of manufacture, as shown.

ALBERT W. BALLENGER.
